(57) **CLAIM**

The ornamental design for an x-ray marker with a hinge, as shown and described.

DESCRIPTION

FIG. 1 is a left side perspective view of an x-ray marker with a hinge showing our new design;

FIG. 2 is a left side perspective view of FIG. 1 shown in an alternate position;

FIG. 3 is a left side perspective view of FIG. 1 shown in an alternate position;

FIG. 4 is a front elevational view thereof;

FIG. 5 is a front elevational view of FIG. 4 shown in an alternate position;

FIG. 6 is a front elevational view of FIG. 4 shown in an alternate position;

FIG. 7 is a rear elevational view thereof;

FIG. 8 is a left side elevational view thereof;

FIG. 9 is a left side elevational view of FIG. 8 shown in an alternate position;

FIG. 10 is a left side elevational view of FIG. 8 shown in an alternate position;

FIG. 11 is a right side elevational view thereof;

FIG. 12 is a right side elevational view of FIG. 11 shown in an alternate position;

FIG. 13 is a right side elevational view of FIG. 11 shown in an alternate position;

FIG. 14 is an enlarged top plan view thereof;

FIG. 15 is an enlarged top plan view of FIG. 14 shown in an alternate position;

FIG. 16 is an enlarged top plan view of FIG. 14 shown in an alternate position;

FIG. 17 is an enlarged bottom plan view thereof;

FIG. 18 is an enlarged bottom plan view of FIG. 17 shown in an alternate position; and,

FIG. 19 is an enlarged bottom plan view of FIG. 17 shown in an alternate position.

1 Claim, 4 Drawing Sheets
